UNITED STATES PATENT OFFICE.

ELLSWORTH A. HAWTHORNE, OF BRIDGEPORT, CONNECTICUT.

ELECTRIC SWITCH.

1,304,564.

Specification of Letters Patent.

Patented May 27, 1919.

Application filed September 24, 1913. Serial No. 791,676.

To all whom it may concern:

Be it known that I, ELLSWORTH A. HAWTHORNE, a citizen of the United States, and a resident of Bridgeport, county of Fairfield, and State of Connecticut, have invented an Improvement in Electric Switches, of which the following description, in connection with the accompanying drawings, is a specification, like characters on the drawing representing like parts.

This invention relates to electric switches, and more especially to switches of the rotary snap type. While the switch is capable of general application, it is particularly useful in controlling lamps of a lighting system for vehicles, and when so used is capable of controlling a head-light, a pilot-light, and a tail-light, in such a manner that in one position of the switch, the head-light only is lighted, in a second position, the head-light and tail-light are lighted, and in a third position, the pilot and tail-lights are lighted, while in a fourth position, all of the lights are shut off.

My invention will be best understood by reference to the following specification, when taken in connection with the accompanying drawings of one illustrative embodiment thereof, while its scope will be more particularly pointed out in the appended claims.

In the drawings:

Figure 1 is an elevation of the switch, with the casing and handle removed;

Fig. 2 is a sectional view on line 2-2 of Fig. 1, but with the handle and casing in place;

Fig. 3 is a sectional view on line 3-3 of Fig. 2;

Fig. 4 is a detail sectional view on line 4-4 of Fig. 1;

Figs. 5, 6, 7 and 8, are diagrams illustrating the switch in its four different positions, and the arrangement of the circuits which it controls.

Referring to the drawings, and to the embodiment of my invention which I have selected for illustration, I have there shown an electric switch of the rotary snap type, having a base 9, which may be formed of any appropriate insulating material, such for example as porcelain. This base supports terminals 10, 11, 12 and 13, appropriately secured to the base, and provided respectively with a set of contacts 14, 15, 16 and 17, all of which are preferably arranged about a

center in one plane. These contacts may be otherwise appropriately arranged, but herein the contacts 14 and 17 are disposed on centers approximately 90 degrees apart, and the contacts 14 and 15 are disposed on centers approximately 90 degrees apart, while the contact 16 is disposed on centers substantially less than 90 degrees from the adjacent contact 15.

The terminal 10 will be referred to as the line terminal since it is intended to be directly connected by a wire to a battery 18, illustrated conventionally in Figs. 5, 6, 7 and 8, while the terminals 11, 12 and 13, are connected respectively by wires to lamps 19, 20 and 21. The other terminals of these lamps may be connected by any appropriate means to the remaining terminal of the battery, but herein they are connected to a metallic ground 22, which may be the frame of a vehicle, and this in turn is connected to the battery.

The switch may be provided with a set of contacts comprising one or more contact plates, but is herein provided with a pair of superposed contact plates 23, each provided with a contact consisting of a small segment 24, and two other contacts in the form of a relatively larger segment 25, by means of which the terminal may be connected in the various relations already referred to. The segments of the upper and lower contact members are arranged to contact with the upper and lower surfaces of the contacts 14, 15, 16 and 17, in a manner similar to many snap switches now in use. When the contact plates 23 are placed in the position shown in Fig. 5, they are out of contact with the contact 14 of the terminal 10, and hence none of the lamps is in circuit with the battery. This is the initial position of the contact members. In the second position of the contact members, that which is shown in Fig. 6, the terminal 10 is connected with the terminal 13, and the lamp 21 is in circuit with the battery.

In the third position, that which is shown in Fig. 7, the contact members connect the terminal 10 with the terminals 11 and 13, and the lamps 19 and 21 are in circuit with the battery. In the fourth position, that which is shown in Fig. 8, the contact members connect the terminal 10 with the terminals 11 and 12, and the lamps 19 and 20 are in circuit with the battery.

Where the switch is used for controlling the lamps of the lighting system of a vehicle, the lamp 19 may be the tail-light, the

lamp 20 may be the pilot light, and the lamp 21 may be the search-light. The system as illustrated is essentially a single wire system,—that is to say, one terminal of each lamp is connected to one of the switch terminals, while the remaining terminal of each lamp is connected to one battery terminal, and the other battery terminal is connected to the remaining terminal of the switch. By this arrangement, the connections are greatly simplified.

The contact plates 23 may be actuated by any other appropriate mechanism, but I have herein chosen to illustrate a switch mechanism of common form, comprising an operating spindle 26 carrying an eccentric 27, the latter being encircled by an eccentric strap 28, having an arm 29 provided with a lug or tooth 30 projecting toward the base 9. The arm 29 is interposed between a pair of lugs 31 on a carrier 32 loosely mounted on the spindle 26. A helical spring 33, encircling the spindle 26, is secured at one end to the carrier 32 and at its other end to a collar 34, non-rotatably mounted on the spindle. This collar is provided with a series of notches 35 to receive the end of the spring and permit the latter to be adjusted and placed under an initial tension. This initial tension of the spring normally holds the tooth or lug 30 against one of a plurality of teeth 36 of a ratchet 37 fixed to the base 9. The number of teeth of the ratchet corresponds to the number of positions of the switch, which in the present instance is four. The operating spindle is herein provided as usual with a knurled handle 38, by means of which the spindle may be turned to operate the switch. A bushing 39, provided at its upper end with an annular flange 40, extends through the base 9, and is provided on the outer face of the latter with a nut 41, by means of which it is secured in place. A washer 42, secured to the lower end of the operating spindle 26 bears against the lower end of the bushing 39, and prevents endwise movement of the spindle. The switch may be provided as usual with a casing 46.

The operation of the switch mechanism is as follows:

When the operating spindle is turned clockwise (Figs. 1 and 3), the tension of the spring is thereby increased, and simultaneously, the eccentric 27 acts to push the tooth 30 of the eccentric strap 28 radially outward until it disengages from the tooth 36 of the ratchet 37 with which it is engaged, whereupon the spring causes the carrier 32 and eccentric strap 28 to rotate until the tooth of the eccentric strap brings up against the next tooth of the ratchet. By this means, the carrier is caused to snap from one position to another in a familiar manner, which will be readily understood

by those skilled in the art. This motion of the carrier is imparted to the contact members 25 by simply securing the latter to the carrier by any appropriate means, as for example, a pair of rivets 43. The contact members are preferably insulated from the carrier by usual insulating washers 44 and bushings 45.

It will now be apparent that the described rotating mechanism acts to impart to the contact members a step by step movement of approximately 90 degrees to each step, and by this means, the contact plates are carried from the initial position illustrated in Fig. 5 to the position shown in Fig. 6, 80 then to the position shown in Fig. 7, and finally to the position shown in Fig. 8, thus causing current to be supplied to the lamps in the order already described. A quarter turn from the position shown in Fig. 8 85 brings the contact members back to the initial position shown in Fig. 5. It will thus be seen that the control of the lamps is effected by the use of a minimum number of terminals and contact members, the number 90 being considerably reduced as compared with switches heretofore employed for the control of lights in the described manner.

While I have herein shown and described one specific embodiment of my invention 95 for illustrative purposes, and have disclosed and discussed in detail the construction and arrangement incidental to one specific application thereof, it is to be understood that the invention is limited neither to the mere 100 details or relative arrangement of parts, nor to its specific embodiment herein shown, but that extensive deviations from the illustrated form or embodiment of the invention 105 may be made, without departing from the principles thereof.

Having thus described my invention, what I claim and desire by Letters Patent to secure is:

1. In an electric switch, the combination 110 of four stationary contacts disposed about an axis, three contacts being spaced on centers at substantially equal distances apart and the fourth being spaced from the nearest contact a distance on centers of less than the 115 space between any two of said three contacts, and a switch element mounted to turn about said axis and having a segmental contact whose length circumferentially is less than the space between any two of said three stationary contacts and having another segmental contact whose length circumferentially is greater than the space between any two of said three stationary contacts.

2. In an electric switch, the combination 125 of four stationary contacts disposed about an axis, three contacts having their centers disposed on centers substantially ninety degrees apart, and the fourth being disposed from the nearest contact a distance on cen- 130

- ters of substantially less than ninety degrees, and a switch element mounted to turn about said axis and having a segmental contact whose length circumferentially is less than 5 the space between any two of said three stationary contacts and having another segmental contact whose length circumferentially is greater than the space between any two of said three stationary contacts.
- 10 3. In an electric switch, the combination of a set of contacts a plurality of which are spaced on centers equal angular distances apart and the remaining contact being spaced a less angular distance from the nearest contact; another set of contacts electrically connected with each other and two of which are spaced on centers the first-mentioned angular distance apart and the third the same angular distance from the nearest contact; 15 and mechanism for producing a step-by-step rotative movement to one of said sets relatively to the other to cause them to coöperate.
- 20 3. In an electric switch, the combination of a set of contacts three of which are spaced on centers ninety degrees apart and the fourth being spaced less than ninety degrees from the nearest contact; a set of three contacts electrically connected with each other, and two of which are spaced on centers ninety degrees apart and the third ninety degrees from the nearest contact; and mechanism for producing a step-by-step rotative movement of ninety degrees to each 30 step to one of said sets relatively to the other to cause them to coöperate.

erate, each step having an angular distance equal to the first-mentioned angular distance.

4. In an electric switch, the combination 25 of a set of four contacts three of which are spaced on centers ninety degrees apart and the fourth being spaced less than ninety degrees from the nearest contact; a set of three contacts electrically connected with each 30 other, and two of which are spaced on centers ninety degrees apart and the third ninety degrees from the nearest contact; and mechanism for producing a step-by-step rotative movement of ninety degrees to each 35 step to one of said sets relatively to the other to cause them to coöperate.

In testimony whereof, I have signed my name to this specification, in the presence of two subscribing witnesses.

ELLSWORTH A. HAWTHORNE.
